[57] CLAIM

The ornamental design for a support bracket for electric rail coverboard, as shown and described.

DESCRIPTION

FIG. 1 is a right side elevational view of a support bracket for electric rail coverboard, showing my new design; the left side thereof, not shown, is the mirror image of the right side;

FIG. 2 is a top plan view thereof;

FIG. 3 is a bottom plan view thereof;

FIG. 4 is a rear elevational view thereof;

FIG. 5 is a view, partly in plan and partly in section, taken in the direction of the arrows along line 5—5 in

FIG. 1;

FIG. 6 is a view, partly in elevation and partly in section, taken in direction of the arrows along line 6—6 in FIG. 1; and,

FIG. 7 is a reduced scale top, front and right side perspective view thereof.

FIG. 1

FIG. 2

FIG. 3

FIG. 5

FIG. 6

FIG. 7

FIG. 7
